US0D1001604S

(12) **United States Design Patent** (10) **Patent No.:** **US D1,001,604 S**
(45) **Date of Patent:** **** Oct. 17, 2023**

(54) **PRESS JAW**

(71) **Applicant:** **STÄUBLI ELECTRICAL CONNECTORS AG**, Allschwil (CH)

(72) **Inventors:** **François Saugues**, Villette d'Anthon (FR); **Dominic Bürgi**, Basel (CH)

(73) **Assignee:** **Stäubli Electrical Connectors AG**, Allschwil (CH)

(**) **Term:** **15 Years**

(21) **Appl. No.:** **35/514,347**

(22) **Filed:** **Nov. 25, 2021**

(80) **Hague Agreement Data**

Int. Filing Date: **Nov. 25, 2021**

Int. Reg. No.: **DM/217617**

Int. Reg. Date: **Nov. 25, 2021**

Int. Reg. Pub. Date: **May 27, 2022**

(30) **Foreign Application Priority Data**

Jun. 1, 2021 (CH) 146.111

(51) **LOC (14) Cl.** **08-05**

(52) **U.S. Cl.**

USPC **D8/52**

(58) **Field of Classification Search**

USPC D8/21, 52, 56, 58, 60; D18/24-33;
D15/123, 126
